US00D714868S

(12) **United States Design Patent**
Nash

(10) **Patent No.:** **US D714,868 S**
(45) **Date of Patent:** **** Oct. 7, 2014**

(54) **NOTE DISPENSER**

(71) Applicant: **3M Innovative Properties Company**,
St. Paul, MN (US)

(72) Inventor: **James E. Nash**, Bloomington, MN (US)

(73) Assignee: **3M Innovative Properties Company**,
St. Paul, MN (US)

(**) Term: **14 Years**

(21) Appl. No.: **29/470,458**

(22) Filed: **Oct. 22, 2013**

(51) LOC (10) Cl. **19-02**
(52) U.S. Cl.
USPC **D19/86**

(58) **Field of Classification Search**

(57) **CLAIM**

The ornamental design for a note dispenser, as shown and described.

DESCRIPTION

FIG. 1 is a perspective view showing the new design for a note dispenser;

FIG. 2 is a front view thereof;

FIG. 3 is a rear view thereof;

FIG. 4 is a right side view thereof, a left side view being a mirror image thereof;

FIG. 5 is a top view thereof;

FIG. 6 is a bottom view thereof; and,

FIG. 7 is a perspective view thereof showing the note dispenser with a note.

The broken lines in Figures are included for the purpose of showing portions that form no part of the claimed design.

1 Claim, 3 Drawing Sheets
